UNITED STATES PATENT OFFICE.

ALBERT W. PEARSALL, OF MOUNT VERNON, NEW YORK, ASSIGNOR TO THE PEARSALL PNEUMATIC TUBE AND POWER CO., OF NEW YORK, N. Y., A CORPORATION OF NEW YORK.

PNEUMATIC-DESPATCH-TUBE CARRIER.

SPECIFICATION forming part of Letters Patent No. 686,680, dated November 12, 1901.

Application filed April 3, 1901. Serial No. 54,207. (No model.)

To all whom it may concern:

Be it known that I, ALBERT W. PEARSALL, a citizen of the United States, residing at Mount Vernon, in the county of Westchester and State of New York, have invented new and useful Improvements in Pneumatic-Despatch-Tube Carriers, of which the following is a specification.

This invention relates to carriers or receptacles adapted for use in pneumatic-despatch tubes; and the invention resides in the novel features of construction set forth in the following specification and claims, and illustrated in the annexed drawings, in which—

15 Figure 1 is a side elevation of the carrier closed. Fig. 2 is a section along $z z$, showing the cover closed. Fig. 3 is a like section showing the cover open. Fig. 4 is an end view of the carrier open. Fig. 5 is an end view showing the cover in the act of being closed. Fig. 20 6 is an end view of the cover closed.

In the drawings the letter a indicates a shell or carrier, and b is a cover mounted on a support or strap c . When open, the cover is 25 swung or moved away from the carrier, so as to be clear from or outside the periphery of the carrier entrance or mouth. The cover is thus out of the way, so as not to interfere with or obstruct the entry or exit of matter 30 to and from the tube. The strap c is hinged at d at the edge or outside of the carrier-mouth, so that no obstruction is formed by or at said hinge to matter entering and leaving the carrier. This cover is eccentrically movable for 35

a purpose presently explained. This eccentric pivot or support e connects the cover to the strap, and a stop or pin f has been found practical, said stop when striking the strap or arresting the cover holding the latter in 40 position for its segmental flange g to swing or come about the carrier when the cover is moved to closing position. On then rotating the cover in the proper direction or so as to carry stop f away from the strap the flange 45 or catch g is made to engage a projection or rib h on the carrier or body a and lock the cover. The open end of the carrier is thus securely closed, and when fitted or slipped into the conveyer-tube, the cover and car-

rier being in concentric position, the cover is 50 locked and is prevented from opening or from rotating about pivot e at least to such a degree as is required to free the cover. Spilling or injury of the carrier contents is thus avoided. The rib h can be formed as a bead 55 about the mouth to strengthen the shell.

A head is shown secured to or forming the closed end of the carrier. This head is more fully described in a separate application and need not be detailed herein. 60

The packing, such as felt or other suitable material used in pneumatic carriers, is shown at t . The nut or screw m' secures the packing or disk t to the cover b , and the eccentric-pins v' , extending into such felt or disk t , 65 prevent rotation of the packing. The nut m' , seated in the packing, can be covered by a suitable plug u , glued or secured in place.

The screw m' is shown flattened or countersunk at its inner end, so as not to interfere with the cover rotating about pivot e or gliding on the strap c . The packing has been removed from the cover in Figs. 5 and 6 for clearness in illustration; but in Fig. 2 the packing is shown at the cover. The eccentric-pins v' can be located at some distance from the center or axis, so as to effectively prevent the felt working loose or rotating about the central screw or bolt m' . The eccentric studs need not extend through the 80 packing, but only pierce into the same sufficiently to secure firm hold or lock against rotation. 75

What I claim as new, and desire to secure by Letters Patent, is— 85

1. A carrier or receptacle having a cover eccentrically movable for locking and unlocking the same and made to swing or move away or clear from the periphery of the carrier-entrance for unobstructed entry and exit substantially as described. 90

2. A carrier or receptacle having a cover eccentrically movable for locking and unlocking the same and a swinging strap or support for the cover to carry the same clear of the 95 carrier on opening, said strap being hinged to the edge of the carrier substantially as described.

3. A ribbed carrier or receptacle open at one end, a strap made to swing over the open end, and an eccentrically-pivoted cover on the strap having a catch or flange to engage 5 the rib of the carrier substantially as described.
4. A ribbed carrier or receptacle open at one end, a strap made to swing over the open end, an eccentrically pivoted or rotating cover 10 on the strap, and a stop for limiting the rotation of the cover, the latter having a catch for engaging the ribbed carrier substantially as described.
5. A carrier or receptacle open at one end, 15 a swinging strap at said open end, and an eccentrically-pivoted cover on the strap made

to engage the carrier, said cover having studs riveted or secured flush to the cover to clear or glide over and be independent of the strap, one of the studs being centrally located so as 20 to be adapted for bolting or securing a felt or packing, and the other stud or studs being located eccentrically to prevent rotation of the packing relatively to the cover.

In testimony whereof I have hereunto set 25 my hand in the presence of two subscribing witnesses.

ALBERT W. PEARSALL.
